UNITED STATES PATENT OFFICE

2,462,806

GLASSWARE FORMING APPARATUS

Edward Danner, Newark, Ohio

Application December 21, 1943, Serial No. 515,089

26 Claims. (Cl. 49—17.1)

1

This invention relates to glassware forming apparatus and, more particularly, to apparatus for forming a stream of molten glass into hollow glass tubing.

Heretofore glass tubing has been manufactured by the formation of a downwardly moving cylinder from a continuous stream of molten glass flowing from an opening in the bottom of the forehearth of the glass-melting tank or from an opening in the bottom wall of the glass-melting tank. Where the glass is first melted in a tank and is permitted to flow into the forehearth and is then drawn from the forehearth, the temperatures prevailing in the forehearth are not of such character as to render it particularly difficult to extend supporting members for the forming mechanism and members carrying cooling fluid and blowing air upwardly through the forehearth. However, where the glass is drawn from the container in which the glass is melted, the temperatures prevailing therein are sufficiently high to make it undesirable to extend supporting members and fluid pipes upwardly through the tank. The present invention is directed primarily to the provision of glassware forming apparatus which is of such character as to render it unnecessary to extend any of the drawing or forming equipment and the supporting mechanism above the bottom wall of the forehearth or tank.

In accordance with the present invention, I provide glassware forming apparatus in which the element or elements for forming the molten glass into ware, the supporting mechanism therefor, the blow pipe for supplying air to the interior of the formed tubing, the pipes for supplying cooling fluid to and withdrawing it from one of the shaping elements, and the apparatus for effecting adjustments of the various parts are positioned below the molten glass in the forehearth or tank and do not extend upwardly therethrough. My invention is not limited to the use of any particular type or types of forming means for forming the molten glass into the ware, but includes the use of one or more shaping elements either alone or in combination with means for sizing the ware internally or externally during the forming operation. In one embodiment shown in the drawings, a single shaping element is utilized, whereas in the other embodiments two or more shaping elements are employed, including an internal sizing member. In all of the embodiments shown in the drawings the principal shaping element is of the general type shown and described in my copending ap-

2

plication Serial No. 380,179, which has now eventuated into Patent No. 2,390,925. This shaping element embodies a plurality of nesting coaxial shells which are spaced radially from each other and constitutes a substantial departure from the types which have been commercially used heretofore. Where this type of shaping element is employed, glass tubing having a relatively thick wall can be formed and both thick and thin-walled tubing can be drawn at appreciably higher rates of speeds than those employed at the present time.

In the accompanying drawings I have shown, for purposes of illustration only, several embodiments of my invention. It will be understood, however, that my invention is not limited to the particular embodiments but may be embodied in various types of apparatus within the scope of the claims appended hereto.

20 In the drawings,

Figure 1 is a central vertical section through a tube-forming apparatus of my invention installed under a glass-melting tank, certain of the parts being shown in elevation;

25 Figure 2 is a horizontal section taken along the plane of line II—II of Figure 1;

Figure 3 is a partial vertical section taken along the plane of line III—III of Figure 2;

30 Figure 4 is a sectional view showing a portion of Figure 1 to enlarged scale with additional parts in section;

Figure 5 is a horizontal section taken along the plane of line V—V of Figure 4;

35 Figure 6 is a vertical central section through one end of the transverse duct extending through the block forming a part of the bottom of the tank;

Figure 6A is a partial vertical section along the plane of line VIA—VIA of Figure 6;

Figure 7 is a partial horizontal section taken along the plane of line VII—VII of Figure 6;

Figure 8 is a partial horizontal section taken along the plane of line VIII—VIII of Figure 4;

45 Figure 9 is a partial vertical section taken along the plane of line IX—IX of Figure 1;

Figures 10 and 10A are partial horizontal sections taken along the planes of lines X—X and XA—XA of Figure 9;

50 Figure 11 is a vertical central section through tube-shaping means generally similar to that shown in Figures 1, 4 and 5, but differing slightly therefrom in detail;

Figure 11A is a section showing a portion of Figure 11 to an enlarged scale;

Figure 12 is a perspective view of a detail;
Figure 13 is a view similar to Figure 4 showing a modified construction;

Figures 14 and 15 are partial horizontal sections taken along the planes of lines XIV—XIV and XV—XV, respectively, of Figure 13;

Figure 16 is a view similar to Figure 4 showing a further modification.

Referring in detail to the drawings and for the present to Figures 1 through 3, I provide a tank 10 adapted to hold a supply of molten glass, having a bottom wall 11 having an opening 11' therein. The tank is supported on columns 12 connected by beams 13. Diagonal beams 14 extend inwardly from the columns to a frusto-conical ring 15. Auxiliary beams 16 extend between adjacent beams 13 and support the diagonal beams 14. Other auxiliary beams 17 extend between adjacent beams 13 and support auxiliary beams 18 extending normal to the beams 13 at their midpoint. The tank 10 is constructed in the known manner by laying up refractory brick on the structural support provided by the columns 12 and the main and auxiliary beams, within the usual binding which may be fabricated from structural members and plates.

A refractory block 19, which abuts the bottom wall of the tank, is positioned within the ring 15 and has a center opening 20 adapted to align with the opening 11' in the bottom of the tank. The block 19 is provided with segmental straps 21 extending circumferentially thereof and bolted together. The block is supported on hanger bars 22 depending from brackets 23 spaced circumferentially of the ring 15. The bars 22 extend between the spaced ends 24 of the straps 21. The block 19 may be, and preferably is, formed of two pieces for constructional purposes.

A passageway 25 extends transversely through the block 19 and intersects the hole 20 therethrough. A metal tube or duct 27 having closed terminal portions 28 removably secured thereto is positioned in the passageway. The portion of the tube within the hole 20 is provided with a protective mass of refractory material 26 set into the block. The block is preferably split along a median horizontal plane to permit the insertion of the mass 26 and the tube 27. An air supply pipe 29 communicates with the tube 27 adjacent one end thereof and an outlet pipe 30 near the opposite end.

Pipes 31 and 31a connected by a T fitting 31b extend longitudinally through the tube 27, having both their outer ends blanked off as shown in Figure 6. Near the outer ends of the pipes pins 32 projecting laterally therefrom rest on wedges 33 carried by a slide 34. The fitting 31b has pins 32' cooperating with wedges 33a. The slide is movable longitudinally in the tube 27 by a screw 35 threaded through the end of one terminal 28 and swiveled to the slide at 36.

A water inlet pipe 6 extends upwardly through a stuffing box 37 depending from one end of the tube 27 and makes connection with the pipe 31 near the outer end thereof. A water outlet pipe 38 similarly extends through a stuffing box 39 depending from the other end of the tube 27 and makes connection with the outer end of pipe 31a. The stuffing boxes 37 and 39 are provided with packing and glands whereby the pipes 31 and 31a may be adjusted vertically in the tube 27 without leakage of air from the interior thereof. It will be apparent that rotation of the screw 35 by means of its hand wheel will cause the slide 34 to move in one direction or the other to raise or

lower the pipe 31 by means of the wedges 33 and 33a.

A pipe 41 depends from the fitting 31b through the hole 20 and is provided at its lower end with a sizing mandrel 42. The mandrel comprises a metal cylinder 43 secured to the pipe 41 having an external layer of graphite 44 applied thereto. A division plate 45 extends longitudinally of the pipe 41 defining separate parallel passages therethrough. A slot 46 is formed on one side of the pipe on the interior of the cylinder 43. The pipe 41 is blanked off at its lower end on the side on which the slot 46 is formed. Cooling fluid supplied by the pipe 6 thus flows through pipe 31, down the right-hand side of pipe 41 and into the cylinder 43. When the cylinder is filled, fluid flows upwardly through the left-hand side of pipe 41 through pipe 31a and thence through the outlet pipe 38.

A tubular shield 47 depending from the tube 27 and communicating therewith, surrounds the upper end of the pipe 41. The tube is provided with an external shield of refractory material. A flange 48 is secured to the lower end of the tube 47. Centering ribs 41a on the pipe 41 keep it coaxial with the tube 47.

A sleeve 49 secured to the pipe 41 just below the flange 48 has radial vanes 50 supporting the inner shells 51 and 52 of a multiple-shell glass-shaping means, the details of which are best shown in Figure 11. The upper and lower edges of the vanes 50 are beveled adjacent the shell 51 as indicated at 53. The shell 52 is supported on the shell 51 by spacer blocks 54a one of which is shown in Figure 12 in a manner which will be explained in greater detail by reference to Figure 11. The remaining shells 54 of the glass-shaping means are supported from the exterior thereof in the manner now to be described.

A forming chamber 55 suspended below the block 19 on hanger bars 56 depending from the structural frame on which the tank 10 is carried, comprises an open-ended hollow cylinder of refractory material laid up within an enclosure including top and bottom rings 57a and 57b and sheathing plates 57c. Brackets 58 projecting from the upper ring are engaged by the hanger rods 56. A bearing ring 59 is disposed within the upper ring 57a and supports a ring 60 having radial webs 61 resting thereon. Centering screws 62 threaded through the ring 57a engage the webs 61. The ring 60 has an internal flange 63 adjacent the bottom thereof. The outer shells 54 of the shaping means are supported on balls 64 resting on the flange 63. The outermost shell 54 has an upper external flange 65 engaging the balls and each of the inner shells 54 is supported on the next outer shell by spacers such as that shown in Figure 12.

The remaining details of the forming chamber 55 are generally similar to those shown in my copending application, Serial No. 423,255, filed December 17, 1941. A fuel-supply manifold 66 is supported below the chamber on brackets 67 secured thereto and is provided with burners 68 for firing upwardly and around the interior of the chamber. A frusto-conical deflector ring 69 is carried on rods 70 extending upwardly from a Y-shaped arm 71. The arm is carried on a rack 72 slidable within a tube 73 on the exterior of the chamber. A housing 74 projecting from the tube 73 has a pinion shaft journaled therein provided with a pinion meshing with the rack 72 and with a hand crank whereby the ring 69 may be raised or lowered.

For controlling the draft upwardly through the chamber 55 and outwardly between it and the block 19, I provide a ring damper 75. The damper is supported on brackets 76 carried by sprocket wheels 77 threaded on studs 78 projecting upwardly from the ring 57a. The sprockets 77 are connected by a chain 79 which also travels over idler sprockets 80. The chain is driven by a sprocket mounted on a shaft 81 threaded in a hub 82 secured to the exterior of the chamber 55 (see Figure 3). Rotation of the shaft 81 causes it and the brackets 76 to move up or down, thus raising or lowering the ring 75.

Figures 11 and 11A show a slight modification of the glass-shaping means of Figure 4, the only difference being that in the shaping means 86' of Figure 11 all the outer shells 54 are carried on the innermost shell 51 by means of spacer blocks like that shown in Figure 12. As there illustrated, these spacers comprise a block notched and beveled on the inside at the upper end and on the outside at the lower end. When positioned as shown in Figures 11 and 11A the spacers serve to support each shell on the next inner shell, each shell being provided with an internal flange 83 and an exterior intermediate band 84. That is to say, the spacers on the outside of each shell rest on the band 84 thereof and support the next outer shell by the engagement therewith with its flange 83. The notched and beveled ends of the spacers facilitate division of the descending annular glass stream and reunion of the several portions thereof. In other respects, the shaping means of Figure 11 is similar to that of Figure 4 and corresponding parts are designated by the same numerals.

In the operation of the apparatus described above, molten glass from the tank 10 flows downwardly from the bottom opening thereof through the hole 20 in the block 19 and around the refractory mass 26 which protects the tube 27. The descending stream is divided by the tube and its protective refractory material but the portions thereof reunite as they flow downwardly around the tube 47 and onto the flange 48. The latter causes the diameter of the stream to increase so that glass flows downwardly through and around the shaping means constituted by the shells 51, 52 and 54 and thence over the sizing mandrel 42, as indicated in chain lines at 85 in Figure 1. The tubular stream of glass thus produced may be drawn into tubing of the desired size and wall thickness depending upon the size of the mandrel, the rate of draw and the rate at which glass flows downwardly from the tank.

As previously indicated, cooling water is circulated through the sizing mandrel 42 and air pressure is maintained within the tubular glass between the tube 47 and the mandrel 42. The burners 68 supply the heat necessary to maintain the glass within the chamber 55 at the desired viscosity. The mandrel 42, of course, imparts to the tubing its final shape and size. The mandrel 42 and the shell 52 may be adjusted vertically relative to the shaping means by turning the screw 35 to actuate the slide 34 as already explained. This adjustment permits regulation of the flow and consequently of the wall thickness of the tubing. It also permits shutting off of the flow of glass when desired. The slide 34 may be moved horizontally to a sufficient extent to bring the upper end of a part of the shaping means 86 into contact with the block 19, thus shutting off the supply of glass to the shaping means except for a small amount which will pass

around the flange 48. Regulation of the glass flow is effected by adjusting at least a portion of the shaping element to an intermediate position in the same way.

Figures 13 through 15 illustrate a modified form of the invention which is adapted for producing tubing of smaller diameter than that for which the apparatus described above is intended. With certain exceptions to be described in detail 10 those parts of the modified form which are similar in construction to the embodiment already illustrated are designated by corresponding numerals. The elements of the modified form which are similar in function to elements of the form first described but differ slightly therefrom in construction are designated by the same reference numerals primed.

The modified apparatus differs from the apparatus previously described principally in the details of the shaping means indicated generally 20 at 86''. The forming chamber 55' is somewhat deeper relative to its diameter than the chamber 55, but is mounted in the same way as the latter and is provided with similar associated parts. 25 The shaping means 86'' is composed of a plurality of radially spaced coaxial shells with spacers 54a therebetween at circumferentially spaced points, each shell being supported on the next inner shell. The innermost shell is carried 30 on a sleeve 87 secured to the pipe 41 depending through the tube 47 from the pipes 31 and 31a in the duct 27. The sleeve 87 has longitudinal slots 88 on the interior thereof whereby air under pressure delivered to the duct 27 through pipe 29 flows downwardly along the pipe 41 and into 35 the space within the annular stream of glass indicated in chain lines at 89. The sleeve 87 also supports a preliminary shaping means in the form of a frusto-conical shell 90 disposed above the shaping means 86''. The shell 90 is supported on radial webs 91 extending inwardly therefrom to the sleeve 87.

The pipe 41 is provided with final shaping means in the form of a sleeve 92 of graphite or 45 the like extending upwardly from its lower end. The sleeve is supported on a disc 93 secured by a screw 94 to a plug 95 welded in the end of the pipe. The pipe 41 has a center division plate 45' terminating short of the lower end of the 50 pipe and defining inlet and outlet passages for cooling fluid in the same manner as the plate 45 of Figure 4. It will doubtless be readily understood from the previous explanation of the embodiment first described, that a stream of molten glass descending through the hole 20 in the block 19 divides in two parts which pass on opposite 55 sides of the duct 27 and its protective refractory mass 26 then reunite as they flow downwardly along tube 47 and onto the flange 48. The glass then flows outwardly and down over the preliminary shaping shell 90. The effect of the shell 90 is to control the flow of glass and to contract the stream somewhat as indicated in the drawing, after which it is subjected to further shaping by 60 the means 86'', air being supplied to the interior of the resulting annular stream as previously described. The glass then flows downwardly around the final sizing sleeve 92. After passing the sizing sleeve, the tubing drawn therefrom is 65 permitted to cool and is cut into the desired lengths after it has become rigid.

Figure 16 illustrates a further modification of the invention which is similar in some respects to those already described. It is a simple construction for the manufacture of small tubing

without the use of a sizing mandrel. In this modification, a refractory block 19' similar to the block 19 is secured to the bottom of a tank 10. A center hole 96 extends vertically through the block 19'. This hole is reduced in diameter at the lower end. A duct 97 closed at its ends extends transversely through the block 19' intersecting the hole 96, the portion of the duct within the opening being enclosed in protective refractory tubing 98. A screw 99 threaded through one of the closed ends 100 of the duct 97 operates a wedge 101 through the medium of a push rod 102 swiveled to the screw at 103.

The wedge 101 supports a pipe 104 which extends downwardly through a tube 105 depending from and communicating with the duct 97. As shown in the drawings, the wedge 101 extends through a slot in the upper end of the pipe 104 and engages a bearing pad 106 formed on the inside of the closed end of the pipe. The pipe has radial centering studs 107 engaging the interior of the tube 105. The latter is protected by a refractory tube 108 in the same manner as the duct 97. A collar 109 on the lower end of the tube 105 supports the protective tube 108. A plug 110 having an axial hole therethrough is secured in the lower end of the pipe 104. Radial pins 111 screwed into the plug 110 support a plurality of spaced coaxial shells 112 which together comprise glass-shaping means generally similar to that previously described.

A refractory disc 113 having a center hole therethrough provided with a metal bushing 114 is supported below the block 19' with its hole coaxial with the hole 96. Centering studs 115 screwed into the collar 109 engage the interior of the bushing 114. The disc is enclosed in circumferential segmental straps 116 connected by bolts 117 having sleeves 118 rotatable thereon. The disc is supported by tapered screws 119 threaded through lugs 120 secured to a ring 121 forming part of the enclosure for the block 95. As shown, the tapered ends of the screws 119 engage the sleeves 118 and force the disc 113 against the bottom of the block 19'. A gasket 122 is disposed between the disc and block.

A forming chamber 123 generally similar to those shown at 55 and 55' is suspended in the same manner as the latter below the block 95 and is provided with the associated parts illustrated in connection with the forms of the invention already explained, which are omitted from Figure 16 to avoid unnecessary repetition in the drawings and description.

The apparatus shown in Figure 16 functions in generally the same way as that previously described. Air is supplied to the duct 97 through a suitable connection (not shown). Glass flows downwardly through the hole 96 and around the sleeve 98 which protects duct 97 and it then flows down around tube 108 which protects tube 105. The disc 113 restricts the flow of glass downwardly onto the shaping means to insure a uniform flow onto the shaping means at a point desired for distribution. Air from the duct 97 enters the pipe 104 through the slots therein, through which the wedge 101 projects, and flows through the hole in the plug 110 into the interior of the tubing being formed. In this embodiment the adjustment of the screw 99 adjusts the wedge 101, and this in turn raises or lowers the pipe 104. If the pipe 104 is raised to the limit of its upward movement, the shells 112 are brought into contact with the block 113. This shuts off the supply of glass except for the small amount which will

pass around the shell of the shaping element positioned immediately below the orifice. Regulation of the flow of the glass is effected by modifying the position of the shaping element with respect to the orifice.

It will be apparent from the foregoing description and explanation that the invention is characterized by numerous advantages over glass-forming apparatus known heretofore. One of these advantages is the fact that the suspension for the glass-shaping means does not pass through the entire depth of the molten glass in the tank. The air supply for the tubing being drawn is introduced at one side of the glass stream flowing downwardly from the tank only a short distance above the shaping means itself. This arrangement protects the necessary duct, pipes, etc. from contact with the molten glass, except over the short distance between the block 19' and the shaping means suspended therebelow.

The invention provides means for adjusting a portion or all of the glass-shaping means vertically, means for adjusting the sizing means vertically with the shaping means, and means for regulating the flow of glass, thus facilitating the production of tubing of the desired wall thickness. I also provide means for supplying cooling fluid to the sizing means to prevent overheating thereof. In addition to the foregoing advantages, the apparatus of my invention is simple in structure, relatively inexpensive to manufacture and easy to operate and maintain.

Although I have illustrated and described but a preferred embodiment with certain modifications, the construction and arrangement of the parts disclosed may be varied materially without departing from the spirit of the invention or the scope of the appended claims.

I claim:

1. Glassware forming apparatus comprising a container for molten glass having a bottom opening, a refractory block supported against the bottom of the container and covering a portion of said opening, said block having a vertical hole therethrough in alignment with said bottom opening, a conduit extending horizontally through said block and intersecting said hole, a tube extending downwardly through said hole, glass-sizing means mounted on said tube, and pipes extending along said conduit for supporting and circulating cooling fluid through said tube.

2. Glassware forming apparatus comprising a container for molten glass having a bottom opening, a refractory block suspended against the bottom of the container and covering a portion of said opening, said block having a vertical hole therethrough in alignment with said bottom opening, means providing a horizontal passage extending through said block, a suspension for glass-sizing means including a vertical tube depending through said hole and pipes branching from said tube and extending along said passage for circulating cooling fluid through said tube.

3. Glassware forming apparatus comprising a molten-glass container having a bottom opening, a refractory block supported against the bottom of the container and covering a portion of said opening, said block having a vertical hole therethrough in alignment with said bottom opening, an air duct extending horizontally through said block and intersecting said hole, a tube extending downwardly through said hole, glass-sizing means mounted on said tube, and pipes extending from said tube along said duct for supporting

the tube and circulating cooling fluid therethrough.

4. The apparatus defined by claim 1 characterized by means in said conduit for adjusting said tube and pipes vertically.

5. The apparatus defined by claim 1 characterized by means in said conduit for adjusting said tube and pipes vertically and means accessible on the exterior of said conduit for actuating said adjusting means.

6. Glassware forming apparatus comprising a container for molten glass having a bottom opening, a refractory block suspended against the bottom of the container and covering a portion of said opening, said block having a vertical hole therethrough in alignment with said bottom opening, an air duct extending horizontally through said block and intersecting said hole, a tube extending downwardly through said hole, glass-sizing means mounted on said tube, pipes extending from said tube along said duct for supporting the tube and circulating cooling fluid therethrough, and a pipe connection for supplying air to said duct.

7. Glassware forming apparatus comprising a container for molten glass having a bottom opening, a refractory block suspended against the bottom of the container and covering a portion of said opening, said block having a vertical hole therethrough in alignment with said bottom opening, an air duct extending horizontally through said block and intersecting said hole, a tube extending downwardly through said hole, glass-sizing means mounted on said tube, pipes extending from said tube along said duct for supporting the tube and circulating cooling fluid therethrough, a pipe connection for supplying air to said duct, and a tubular shield surrounding the upper end of said tube, said shield communicating with the duct.

8. Glassware forming apparatus comprising a container for molten glass having a bottom opening, a refractory block supported against the bottom of the container and covering a portion of said opening, said block having a vertical hole therethrough in alignment with said bottom opening, an air duct extending substantially horizontally through said block and intersecting said hole, a tube extending downwardly through said hole, glass-sizing means mounted on said tube, pipes extending from said tube along said duct for supporting the tube and circulating cooling fluid therethrough, and inlet and outlet connections to said pipes extending through the duct at points outwardly of said block.

9. Glassware forming apparatus comprising a container for molten glass having a bottom opening, a refractory block supported against the bottom of the container and covering a portion of said opening, said block having a vertical hole therethrough in alignment with said bottom opening, an air duct extending horizontally through said block and intersecting said hole, a tube extending downwardly through said hole, glass-sizing means mounted on said tube, a pipe extending from said tube along said duct for supporting the tube and circulating cooling fluid therethrough, inlet and outlet connections to said pipe extending through the duct at points outwardly of said block, and wedge means movable longitudinally in the duct for adjusting said tube, pipe and connections.

10. Glassware forming apparatus comprising a molten-glass container having a bottom opening, a refractory block supported against the bottom

of the container and covering a portion of said opening, said block having a vertical hole therethrough in alignment with said bottom opening, a forming chamber suspended below said block, a ring having a diameter less than the inside diameter of the chamber supported on the upper end of the latter, and glass-shaping means comprising a plurality of nesting coaxial shells seated in said ring substantially coaxially with said hole.

10. 11. The apparatus defined by claim 10 characterized by means on said chamber for centering said ring relative to said hole.

12. Glassware forming apparatus comprising a molten-glass container having a bottom opening, 15 a refractory block supported against the bottom of the container and covering a portion of said opening, said block having a vertical hole therethrough in alignment with said bottom opening, a conduit extending through said block and intersecting said hole, a tube extending downwardly through said hole, means in the conduit for supporting the tube, and glass-shaping means, at least a portion of said shaping means being mounted on said tube.

13. Glassware forming apparatus comprising a molten-glass container having a bottom opening, a refractory block supported against the bottom of the container and covering a portion of said opening, said block having a vertical hole therethrough in alignment with said bottom opening, 30 a forming chamber suspended below said block, a plurality of coaxial, nesting shells disposed substantially in alignment with said hole, and means for supporting said shells.

14. Glassware forming apparatus comprising a molten-glass container having a bottom opening, a refractory block supported against the bottom of the container and covering a portion of said opening, said block having a vertical hole therethrough in alignment with said bottom opening,

40 a supporting member extending horizontally through said block and intersecting said hole, a support depending from said member, a sizing member mounted on said support, a forming 45 chamber below said block and a plurality of nesting coaxial shells supported in said chamber coaxially of said hole and above said sizing member.

15. Glassware forming apparatus comprising a molten-glass container having a bottom opening, 50 a refractory block supported against the bottom of the container and covering a portion of said opening, said block having a vertical hole therethrough in alignment with said bottom opening, a supporting member extending horizontally through said block and intersecting said hole, a support depending from said member, a sizing member mounted on said support, a plurality of nesting coaxial shells, at least a part of said shells being mounted on said support above said sizing means, a tubular shield surrounding the upper portion of said support, and a flange on said shield deflecting glass flowing down said shield outwardly to said shells.

16. Glassware forming apparatus comprising 65 a molten-glass container having a bottom opening, a refractory block supported against the bottom of the container and covering a portion of said opening, said block having a vertical hole therethrough in alignment with said bottom opening, a supporting member extending horizontally through said block and intersecting said hole, a support depending from said member, a sizing member mounted on said support, shaping means positioned above said sizing member, including coaxial nesting shells disposed coaxially

with said hole, at least a portion of said shaping means being mounted on said support, and means for spreading glass flowing through said hole and causing it to flow onto said shells.

17. Glassware forming apparatus comprising a molten-glass container having a bottom opening, a refractory block supported against the bottom of the container and covering a portion of said opening, said block having a vertical hole therethrough in alignment with said bottom opening, a supporting member extending through said block and intersecting said hole, a support depending from said member, and shaping means including a plurality of nesting coaxial shells, at least a portion of said shaping means being mounted on said support.

18. Glassware forming apparatus comprising a molten-glass container having a bottom opening, a refractory block supported against the bottom of the container and covering a portion of said opening, said block having a vertical hole therethrough in alignment with said bottom opening, an air duct extending horizontally through said block and intersecting said hole, a blow-pipe extending downwardly through said hole, adjustable means for supporting the pipe, said pipe communicating with said duct, and glass-shaping means including a plurality of nesting coaxial shells, at least a portion of said shaping means being mounted on said pipe.

19. The apparatus defined by claim 18 characterized by means movable in said duct for adjusting the blow-pipe supporting means vertically.

20. The apparatus defined by claim 18 characterized by means movable in said duct for adjusting the blow-pipe supporting means and means operable on the exterior of said duct for actuating said adjusting means.

21. Glassware forming apparatus comprising a molten glass container having a bottom opening, a refractory block supported against the bottom of the container and covering a portion of said opening, said block having a vertical hole therethrough in alignment with said bottom opening, a supporting member extending horizontally through said block and intersecting said hole, a support depending from said member, a sizing member positioned on said support, and shaping means positioned above said sizing member, said shaping means including coaxial nesting shells disposed coaxially with said hole, at least a portion of said shaping means being mounted on said support.

22. Glassware forming apparatus comprising a source of molten glass, a wall having an orifice therethrough communicating with the source of molten glass and providing a downwardly flowing stream of molten glass, a conduit intersecting said orifice, and means for controlling the flow of glass through said orifice, said means comprising a control member adapted to cooperate with the said wall adjacent the orifice and operating means extending into and through at least a part of said conduit and connected to said control member.

23. Glassware forming apparatus comprising a source of molten glass, a wall having an orifice therethrough communicating with the source of

molten glass and providing a downwardly flowing stream of molten glass, a conduit intersecting said orifice, a shaping element positioned to receive the downwardly flowing stream of glass, and means extending into the conduit and connected to the shaping element for adjusting at least a portion of the shaping element relative to said wall containing said orifice for controlling the flow of glass therethrough.

24. Glassware forming apparatus comprising a source of molten glass, a wall having an orifice therethrough communicating with the source of molten glass and providing a downwardly flowing stream of molten glass, a conduit intersecting said orifice, a shaping element positioned to receive the downwardly flowing stream of glass, means extending into the conduit for supporting the shaping element, and means for adjusting the shaping element supporting means vertically with respect to said wall containing said orifice.

25. Glassware forming apparatus comprising a source of molten glass, a wall having an orifice therethrough communicating with the source of molten glass and providing a downwardly flowing stream of molten glass, a conduit intersecting said orifice, a hollow shaping element positioned to receive the downwardly flowing stream of glass, a blow-pipe having one end communicating with said conduit, means for supporting the blow-pipe axially of the orifice, the other end of said blow-pipe supporting said shaping element and communicating with the interior thereof, and means extending into the conduit and connected to the shaping element, blow pipe supporting means for adjusting the blow pipe and vertically with reference to the wall containing said orifice.

26. Glassware forming apparatus comprising a source of molten glass, a wall having an orifice therethrough communicating with the source of molten glass and providing a downwardly flowing stream of molten glass, a conduit intersecting said orifice, a shaping element positioned to receive the downwardly flowing stream of glass, a hollow sizing member positioned below the shaping element, means for supporting the sizing member and shaping element within the downwardly flowing body of glass, said supporting means including a pipe extending through said conduit and communicating with said sizing member for supplying cooling fluid interiorly of the sizing member, and means in said conduit for adjusting said supporting means relative to the wall containing said orifice.

Certificate of Correction

Patent No. 2,462,806.

February 22, 1949.

EDWARD DANNER

It is hereby certified that errors appear in the printed specification of the above numbered patent requiring correction as follows:

Column 5, line 58, after the word "glass" insert *stream*; column 7, lines 42 and 49 respectively, for "block 95" read *block 19*; line 63, for "onto he" read *onto the*; and that the said Letters Patent should be read with these corrections therein that the same may conform to the record of the case in the Patent Office.

Signed and sealed this 30th day of August, A. D. 1949.

[SEAL]

THOMAS F. MURPHY,
Assistant Commissioner of Patents.
